[57] **CLAIM**

The ornamental design for a wall wash light fixture for tracking lighting system, as shown and described.

DESCRIPTION

FIG. 1 is a perspective view of a wall wash light fixture for a track lighting system showing my new design; FIG. 2 is a front elevational view thereof in an enlarged scale;

FIG. 3 is a right side elevational view thereof in an enlarged scale, the left side being a mirror image; FIG. 4 is a top plan view thereof in an enlarged scale; FIG. 5 is a rear elevational view thereof in an enlarged scale;

FIG. 6 is a bottom plan view thereof in an enlarged scale;

The supporting bracket and interior lamp are shown in broken lines for illustrative purposes only.
